US0D1077372S

(12) **United States Design Patent** (10) **Patent No.:** **US D1,077,372 S**
(45) **Date of Patent:** **** May 27, 2025**

(54) **HORSE SHOE**

(71) Applicant: **EASYCARE, INC.**, Durango, CO (US)

(72) Inventor: **Garrett N Ford**, Durango, CO (US)

(73) Assignee: **Easycare, Inc.**

(**) Term: **15 Years**

(21) Appl. No.: **29/837,103**

(22) Filed: **May 2, 2022**

(51) **LOC (15) Cl.** **30-01**

(52) **U.S. Cl.**

USPC **D30/147**

(58) **Field of Classification Search**

USPC D30/144, 145, 146, 147, 148, 149, 151, D30/152, 158, 161, 199; D24/110.1, 124, D24/126, 188, 189, 190, 192; D2/719, D2/743, 744, 747, 860, 882, 892, 897, D2/909, 919, 980; D29/101.1, 101.5, D29/104, 112; D16/242; D14/205

Alejandro J. Fernandez

(57) **CLAIM**

The ornamental design for a horse shoe, as shown and described.

DESCRIPTION

FIG. 1 is a top left perspective view of a horse shoe showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom view thereof.

In the drawings, the equal-length broken lines depict portions of the horse shoe that form no part of the claimed design.

1 Claim, 6 Drawing Sheets
